US010625114B2

(12) **United States Patent**
Ercanbrack

(10) **Patent No.:** US 10,625,114 B2
(45) **Date of Patent:** Apr. 21, 2020

(54) **ELLIPTICAL AND STATIONARY BICYCLE APPARATUS INCLUDING ROW FUNCTIONALITY**

(71) Applicant: **ICON Health & Fitness, Inc.**, Logan, UT (US)

(72) Inventor: **Gaylen Ercanbrack**, Logan, UT (US)

(73) Assignee: **ICON Health & Fitness, Inc.**, Logan, UT (US)

(*) Notice: Subject to any disclaimer, the term of this patent is extended or adjusted under 35 U.S.C. 154(b) by 89 days.

(21) Appl. No.: **15/787,466**

(22) Filed: **Oct. 18, 2017**

(65) **Prior Publication Data**

US 2018/0117393 A1 May 3, 2018

ELLIPTICAL AND STATIONARY BICYCLE APPARATUS INCLUDING ROW FUNCTIONALITY

RELATED APPLICATIONS

This application claims priority to U.S. patent application Ser. No. 62/416,030 titled "Elliptical and Stationary Bicycle Apparatus Including Row Functionality" and filed on 1 Nov. 2016, which application is herein incorporated by reference for all that it discloses.

BACKGROUND

Aerobic exercise is a popular form of exercise that improves one's cardiovascular health by reducing blood pressure and providing other benefits to the human body. Aerobic exercise generally involves low intensity physical exertion over a long duration of time. Generally, the human body can adequately supply enough oxygen to meet the body's demands at the intensity levels involved with aerobic exercise. Popular forms of aerobic exercise include running, jogging, swimming, and cycling, among others activities. In contrast, anaerobic exercise often involves high intensity exercises over a short duration of time. Popular forms of anaerobic exercise include strength training and short distance running.

Many people choose to perform aerobic exercises indoors, such as in a gym or their home. Often, a user will use an aerobic exercise machine to have an aerobic workout indoors. One such type of aerobic exercise machine is an elliptical exercise machine, which often includes foot supports that move in fixed reciprocating directions when moved by the feet of a user. Often, the foot supports are mechanically linked to arm levers that can be held by the user during the workout. The arm levers and foot supports move together and collectively provide resistance against the user's motion during the user's workout. Other popular exercise machines that allow a user to perform aerobic exercises indoors include treadmills, rowing machines, and stepper machines, to name a few.

Another popular form of aerobic exercise is cycling. Cycling is typically done on stationary bikes indoors or on moving bikes outside that travel off road or on streets. With a traditional upright bicycle, the user rests his or her body weight entirely on a small portion of the bike's seat, handles, and pedals. With an upright bike, the user typically leans forward as he or she pedals. Another form of cycling is recumbent cycling. With a recumbent bicycle, the user is often reclined in a seat with a back support which distributes the user's weight over a larger area, including the user's back.

One system for cycling is disclosed in U.S. Pat. No. 6,071,215 issued to David M. Raffo, et al. In this reference, a multi-mode exercise machine has a re-configurable arm member operable in alternate upstanding and recumbent configurations that allows the machine to be used, when the re-configurable arm member is configured in its upright configuration, to provide a first mode of exercise where the user is supported in such an upright position as to be able to exercise at least his/her lower body, and that allows the machine to be used, when the re-configurable arm member is configured in its recumbent configuration, to provide a second mode of exercise, where the user is supported in such a recumbent position as to allow the user to exercise at least his/her upper body. According to Raffo, the re-configurable arm member includes a pivotally mounted and self-locking

arm member movable between a first, upright position and a second, recumbent position. The first and second exercise modes include cycling and rowing exercise modes. Other types of cycling devices are disclosed in U.S. Pat. No. 6,497,426 issued to James L. Vanpelt; U.S. Pat. No. 6,648,353 to Pedro Pablo Cabal; and U.S. Patent Publication No. 2013/0260964 issued to Benjamin Chia.

SUMMARY

In one embodiment, an exercise machine includes a frame, a seat track of the frame, a seat movably attached to the seat of the frame, a first flywheel connected to the frame, a second flywheel connected to the frame, a pull cable in communication with the first flywheel, a crank assembly in communication with the second flywheel, a first swing arm connected to the frame, and a second swing arm connected to the frame.

The exercise machine may include a first magnetic resistance mechanism that resists movement of the first flywheel.

The exercise machine may include a second magnetic resistance mechanism that resists movement of the second flywheel.

The crank assembly may include a crank axle, a first crank arm connected to a first side of the crank axle, a second crank arm connected to a second side of the crank axle, a first crank pedal connected to the first crank arm, and a second crank pedal connected to the second crank arm.

The crank assembly may a crank wheel connected to the crank axle.

The exercise machine may include a transmission medium that transmits torque from the crank wheel to the second flywheel when the crank axle rotates.

The first crank pedal and the second crank pedal may travel in a generally circular path when the crank axle rotates.

The exercise machine may include a base connected to the frame, a first movable linkage pivotally connected to the first side of the crank axle and slidably connected to the base, and a second movable linkage pivotally connected to the second side of the crank axle and slidably connected to the base.

The base may include a first longitudinal track and a second longitudinal track aligned with the first longitudinal track. The first movable linkage connects in the first longitudinal track, and the second movable linkage connects in the second longitudinal track.

The first swing arm may be pivotally connected to the first movable linkage, and the second swing arm may be pivotally connected to the second movable linkage.

The exercise machine may include a first linkage pedal connected to a first mid-region of the first movable linkage and a second linkage pedal connected to a second mid-region of the second movable linkage.

The first linkage pedal and the second linkage pedal may travel in a generally oblong path when the crank axle rotates.

The first longitudinal track and the second longitudinal track may be aligned with the seat track.

The exercise machine may include a handle attached to a first cable end of the pull cable and a cable axle in communication with a second cable end.

The exercise machine may include a transmission medium connecting the cable axle to the first flywheel.

In an embodiment, an exercise machine includes a frame, a seat track of the frame, a seat movably attached to the seat of the frame, a first flywheel connected to the frame, a second flywheel connected to the frame, a pull cable in communication with the first flywheel, a crank assembly in

communication with the second flywheel. The crank assembly includes a crank axle, a first crank arm connected to a first side of the crank axle, a second crank arm connected to a second side of the crank axle, a first crank pedal connected to the first crank arm, and a second crank pedal connected to the second crank arm, a first swing arm connected to the frame, a base connected to the frame, a first movable linkage pivotally connected to the first side of the crank axle and slidably connected to the base, a second movable linkage pivotally connected to the second side of the crank axle and slidably connected to the base. The exercise machine further includes a first longitudinal track, a second longitudinal track aligned with the first longitudinal track, a first linkage pedal connected to a first mid-region of the first movable linkage, and a second linkage pedal connected to a second mid-region of the second movable linkage. The first movable linkage connects in the first longitudinal track, and the second movable linkage connects in the second longitudinal track. The first swing arm is pivotally connected to the first movable linkage, and the second swing arm is pivotally connected to the second movable linkage. The first longitudinal track and the second longitudinal track are aligned with the seat track.

The first linkage pedal and the second linkage pedal may travel in a generally oblong path when the crank axle rotates.

The exercise machine may include a handle attached to a first cable end of the pull cable and a cable axle in communication with a second cable end.

The exercise machine may include a transmission medium connecting the cable axle to the first flywheel.

In an embodiment, an exercise machine includes a frame, a seat track of the frame, a seat movably attached to the seat of the frame, a first flywheel connected to the frame, a second flywheel connected to the frame, a pull cable in communication with the first flywheel, a crank assembly in communication with the second flywheel. The crank assembly includes a crank axle, a first crank arm connected to a first side of the crank axle, a second crank arm connected to a second side of the crank axle, a first crank pedal connected to the first crank arm, and a second crank pedal connected to the second crank arm. The exercise machine includes a crank transmission medium that transmits torque from the crank assembly to the second flywheel when the crank axle rotates, a first swing arm connected to the frame, a second swing arm connected to the frame, a base connected to the frame, a first movable linkage pivotally connected to the first side of the crank axle and slidably connected to the base, and a second movable linkage pivotally connected to the second side of the crank axle and slidably connected to the base, a first longitudinal track, a second longitudinal track aligned with the first longitudinal track, a first linkage pedal connected to a first mid-region of the first movable linkage, a second linkage pedal connected to a second mid-region of the second movable linkage, a handle attached to a first cable end of the pull cable, a cable axle in communication with a second cable end, and a pull transmission medium connecting the cable axle to the first flywheel. The first movable linkage connects in the first longitudinal track, and the second movable linkage connects in the second longitudinal track. The first swing arm is pivotally connected to the first movable linkage, and the second swing arm is pivotally connected to the second movable linkage. The first longitudinal track and the second longitudinal track are aligned with the seat track. The first linkage pedal and the second linkage pedal travel in a generally oblong path when the

crank axle rotates and the first crank pedal and the second crank pedal travel in a generally circular path when the crank axle rotates.

In one embodiment, an exercise machine includes a frame, a seat track of the frame, a seat movably attached to the seat of the frame, a flywheel connected to the frame, a pull cable in communication with the flywheel, a crank assembly in communication with the flywheel, a first swing arm connected to the frame, and a second swing arm connected to the frame.

The crank assembly may include a crank axle, a first crank arm connected to a first side of the crank axle, a second crank arm connected to a second side of the crank axle, a first crank pedal connected to the first crank arm, and a second crank pedal connected to the second crank arm.

The crank assembly may include a crank wheel connected to the crank axle.

The exercise machine may include a transmission medium that transmits torque from the crank wheel to the flywheel when the crank axle rotates.

The exercise machine may include a magnetic resistance mechanism that resists movement of the flywheel.

The first crank pedal and the second crank pedal may travel in a generally circular path when the crank axle rotates.

The exercise machine may include a base connected to the frame, a first movable linkage pivotally connected to the first side of the crank axle and slidably connected to the base, and a second movable linkage pivotally connected to the second side of the crank axle and slidably connected to the base.

The base may include a first longitudinal track and a second longitudinal track aligned with the first longitudinal track. The first movable linkage may connect in the first longitudinal track, and the second movable linkage may connect in the second longitudinal track.

The first swing arm may be pivotally connected to the first movable linkage, and the second swing arm may be pivotally connected to the second movable linkage.

The exercise machine may include a first linkage pedal connected to a first mid-region of the first movable linkage and a second linkage pedal connected to a second mid-region of the second movable linkage.

The first linkage pedal and the second linkage pedal may travel in a generally oblong path when the crank axle rotates.

The first longitudinal track and the second longitudinal track may be aligned with the seat track.

The exercise machine may include a handle attached to a first cable end of the pull cable and a cable axle in communication with a second cable end.

The exercise machine may include a transmission medium connecting the cable axle to the flywheel.

In one embodiment, an exercise machine includes a frame, a seat track of the frame, a seat movably attached to the seat of the frame, a flywheel connected to the frame, a pull cable in communication with the flywheel, and a crank assembly in communication with the flywheel. The crank assembly includes a crank axle, a first crank arm connected to a first side of the crank axle, a second crank arm connected to a second side of the crank axle, a first crank pedal connected to the first crank arm, and a second crank pedal connected to the second crank arm. The exercise machine includes a first swing arm connected to the frame, a base connected to the frame, a first movable linkage pivotally connected to the first side of the crank axle and slidably connected to the base, and a second movable linkage pivotally connected to the second side of the crank axle and slidably connected to the base, and a second swing arm connected to the frame, a base connected to the frame, a first movable linkage pivotally connected to the first side of the crank axle and slidably connected to the base, and a second movable linkage pivotally connected to the second side of the crank axle and

slidably connected to the base, a first longitudinal track, a second longitudinal track aligned with the first longitudinal track, a first linkage pedal connected to a first mid-region of the first movable linkage, and a second linkage pedal connected to a second mid-region of the second movable linkage. The first movable linkage connects in the first longitudinal track, and the second movable linkage connects in the second longitudinal track. The first swing arm is pivotally connected to the first movable linkage, and the second swing arm is pivotally connected to the second movable linkage. The first longitudinal track and the second longitudinal track are aligned with the seat track.

The exercise machine may include a transmission medium that transmits torque from the crank assembly to the flywheel when the crank axle rotates.

The first linkage pedal and the second linkage pedal may travel in a generally oblong path when the crank axle rotates.

The exercise machine may include a handle attached to a first cable end of the pull cable and a cable axle in communication with a second cable end.

The exercise machine may include a transmission medium connecting the cable axle to the flywheel.

In one embodiment, an exercise machine includes a frame, a seat track of the frame, a seat movably attached to the seat of the frame, a flywheel connected to the frame, a pull cable in communication with the flywheel, and a crank assembly in communication with the flywheel. The crank assembly includes a crank axle, a first crank arm connected to a first side of the crank axle, a second crank arm connected to a second side of the crank axle, a first crank pedal connected to the first crank arm, and a second crank pedal connected to the second crank arm. The exercise machine includes a crank transmission medium that transmits torque from the crank assembly to the flywheel when the crank axle rotates, a first swing arm connected to the frame, a second swing arm connected to the frame, a base connected to the frame, a first movable linkage pivotally connected to the first side of the crank axle and slidably connected to the base, a second movable linkage pivotally connected to the second side of the crank axle and slidably connected to the base, a first longitudinal track, a second longitudinal track aligned with the first longitudinal track, a first linkage pedal connected to a first mid-region of the first movable linkage, a second linkage pedal connected to a second mid-region of the second movable linkage, a handle attached to a first cable end of the pull cable, a cable axle in communication with a second cable end, and a pull transmission medium connecting the cable axle to the flywheel. The first movable linkage connects in the first longitudinal track, and the second movable linkage connects in the second longitudinal track. The first swing arm is pivotally connected to the first movable linkage, and the second swing arm is pivotally connected to the second movable linkage. The first longitudinal track and the second longitudinal track are aligned with the seat track. The first linkage pedal and the second linkage pedal travel in a generally oblong path when the crank axle rotates and the first crank pedal and the second crank pedal travel in a generally circular path when the crank axle rotates.

BRIEF DESCRIPTION OF THE DRAWINGS

The accompanying drawings illustrate various embodiments of the present apparatus and are a part of the specification. The illustrated embodiments are merely examples of the present apparatus and do not limit the scope thereof.

FIG. 1 illustrates a side view of an example of an exercise machine in accordance with the present disclosure.

FIG. 2 illustrates a top view of an example of an exercise machine in accordance with the present disclosure.

FIG. 3 illustrates a side view of an example of a user performing an exercise with an exercise machine in accordance with the present disclosure.

FIG. 4 illustrates a side view of an example of a user performing an exercise with an exercise machine in accordance with the present disclosure.

FIG. 5 illustrates a side view of an example of a user performing an exercise with an exercise machine in accordance with the present disclosure.

FIG. 6 illustrates a side view of an example of a resistance mechanism in an exercise machine in accordance with the present disclosure.

FIG. 7 illustrates a side view of an example of a resistance mechanism in an exercise machine in accordance with the present disclosure.

Throughout the drawings, identical reference numbers designate similar, but not necessarily identical, elements.

DETAILED DESCRIPTION

For purposes of this disclosure, the term "aligned" means parallel, substantially parallel, or forming an angle of less than 35.0 degrees. For purposes of this disclosure, the term "transverse" means perpendicular, substantially perpendicular, or forming an angle between 55.0 and 125.0 degrees. Also, for purposes of this disclosure, the term "length" means the longest dimension of an object. Also, for purposes of this disclosure, the term "width" means the dimension of an object from side to side. Often, the width of an object is transverse the object's length.

FIGS. 1 and 2 depict an example of an exercise machine 100 with a frame 102. The frame 102 may include an upright portion 104 and a base 106. The upright portion 104 of the frame 102 can be connected to a seat track 108 that extends horizontally away from the upright portion 104. A leg 112 may extend from the base 106 and support a distal end 112 of the seat track 108. A seat 114 may be movably attached to the seat track 108 so that the seat 114 can slide along a length of the seat track 108.

The upright portion 104 may support a pull cable 116. A first end of the pull cable 116 may be attached to a handle 120, and a second end of the pull cable 116 may be attached to a resistance mechanism (not shown). In some examples, the resistance mechanism is contained within a housing 126 that is connected to the upright portion 104 of the frame 102. In those circumstances when the pull cable 116 is pulled, the resistance mechanism resists the longitudinal movement of the pull cable 116. The housing, the upright portion, or another portion of the exercise machine may include a push pad 128. A user may sit on the seat 114, and place his or her feet against the push pads 128. The user may slide along the length of the seat track 108 by extending his or her legs and/or bending his or her knees. As the user's seat 114 slides away from the upright portion 104 of the frame 102, the user may lean back and pull the pull cable 116 as part of a rowing exercise. As the user travels towards the upright portion 104 of the frame 102, the pull cable 116 may longitudinally move to return to its original position.

The base 106 may include at least one structural member 130 that is transverse the upright portion 104. In some examples, the base includes multiple structural members that are aligned with each other and also transverse the upright portion. The base 106 may include a first linkage

track 132 and a second linkage track 200. In some cases, the first linkage track 132 is formed on a first side of the base 106, and the second linkage track 200 may be formed on a second side of the base 106. In other examples, the first and second linkage tracks 132, 200 are incorporated into the base 106 on a top side. The first linkage track 132 and the second linkage track 200 can be aligned with the seat track 108.

A crank assembly 134 may be included in the exercise machine 100. In some examples, the crank assembly 134 is supported by the base 106. In other examples, the crank assembly 134 is supported by a section of the upright portion 104. The crank assembly 134 may include a crank axle 136, a first crank arm 138 connected to the crank axle 136, and a second crank arm 202 connected to the crank axle 136. A first crank pedal 140 may be attached to the first crank arm 138, and a second crank pedal 204 may be attached to a second crank arm 202. When the crank axle 136 is rotated, the first crank pedal 140 and the second crank pedal 204 may travel in a generally circular path.

A first swing arm 142 may be pivotally attached to a first side of the upright portion 104, and a second swing arm 144 may be pivotally attached to a second side of the upright portion 104. A first swing handle 145 may be attached to an upper portion of the first swing arm 142, and a second swing handle 148 may be attached to an upper portion of the second swing arm 144. A bottom portion of the first swing arm 142 may be connected to a first movable linkage 146, and a bottom portion of the second swing arm 144 may be connected to a second movable linkage 206. The first movable linkage 146 may have an end 150 that slides along the length of the first linkage track 132 of the base 106, and the second movable linkage 206 may have an end 152 that slides along the length of the second linkage track 200 of the base 106. The other end 154 of the first movable linkage 146 may be connected to the first crank arm 138, and the other end 156 of the second movable linkage 206 may be connected to the second crank arm 202. A first linkage pedal 158 may be incorporated into a first mid-region 160 of the first movable linkage 146, and a second linkage pedal 208 may be incorporated into a second mid-region 210 of the second movable linkage 206. The first and second linkage pedals 158, 208 may travel in an oblong path when the crank axle 136 rotates.

FIG. 3 depicts an example of a user 300 performing a cycling exercise. In this example, the user has his feet on the crank pedals 302 and the user is seated in the seat 304. As the user pushes on the crank pedals 302, the crank axle 306 moves causing the crank pedals 302 to move in a generally circular path. In this example, the seat 304 can be locked in place. Multiple openings 308 may be formed in the underside of the seat track 310. A pin 312 may be secured through one of the openings 308 to prevent the seat from sliding along the seat track 310. As the crank axle 306 is rotated, the movable linkages 314 and linkage pedals 316 move accordingly.

FIG. 4 depicts an example of a user 400 performing an elliptical training exercise with the exercise machine 402. In this example, the user is standing with his feet on the linkage pedals 404. The user may optionally support himself by holding onto the swing arms 406. As the user moves the linkage pedals 404, the linkage pedals 404 travel in an oblong path 407. In this example, as the crank axle 408 rotates, the crank pedals 410 and the crank arms 412 move accordingly.

FIG. 5 depicts an example of a user 500 performing a rowing exercise with the exercise machine 502. In this example, the user has his feet secured against the push pads

504, holding the handle 506 of the pull cable 508, and sitting in the seat 510. As the user straightens his legs, the seat 510 slides along the seat track 512 and the pull cable 508 moves longitudinally against the resistance force of the resistance mechanism. On the return stroke, the user 500 bends his knees moving his body back towards the exercise machine's upright portion 514 and the pull cable 508 moves longitudinally to its original position. In some examples, the pull cable 508 is decoupled from the crank assembly so that the crank axle 516 and therefore the crank pedals 518 and linkage pedals 520 do not move based on the longitudinal movement of the pull cable 508.

FIG. 6 depicts an example of the resistance mechanism 600. In this example, the resistance mechanism 600 includes 10 a crank wheel 602 concentrically connected to the crank axle 604. The crank axle 604 is supported by a beam 606 that is attached to a frame member 608 of the upright portion and a leg 612 connected to a base member 614 of the frame.

A first transmission medium 616, such as a drive belt, 20 chain, loop, rope, cable, band, and so forth, is secured around the circumference 618 of the crank wheel. In other examples, the first transmission medium 616 can be secured around a portion of the crank axle's circumference. The first transmission medium 616 connects the crank wheel/crank axle to a first axle 620 of a first flywheel 622. A first magnetic unit 624 may be positioned adjacent the first flywheel 622 so that the first magnetic unit 624 resists the flywheel's movement. This resistance may be transmitted back through the first transmission medium 616, and the 25 crank axle's rotational movement is resisted. As a result, the movement of the crank pedals and the linkage pedals is also resisted.

The pull cable 626 is also routed by the frame member 30 608 of the upright portion. A second end 628 of the pull cable 626 is connected to a pull cable axle 630 which is supported by the beam 606, but may be connected to another portion of the exercise machine in other examples. A second transmission medium 632 connects the pull cable axle 630 to a second axle 634 of a second flywheel 636. A second magnetic unit 638 may be positioned adjacent the second flywheel 636 so that the second magnetic unit 638 resists the flywheel's movement. This resistance may be transmitted back through the second transmission medium 632 to the 35 pull cable axle and thereby resist the longitudinal movement of the pull cable 626. In this example, the movement of the crank axle 604 and the movement of the pull cable axle 630 are independent so that movement of the one of these axles does not cause the rotation of the other. Thus, when the pull cable is moved, the crank pedals and the linkage pedals 40 do not move accordingly. Likewise, when the crank pedals and/or linkage pedals are moved, no additional resistance is placed on the pull cable.

FIG. 7 depicts an example of a resistance mechanism 700. In this example, the crank wheel 702 and the pull cable axle 55 704 are connected to the same flywheel 706. In this example, the first transmission medium 708 and the second transmission medium 710 are connected to the flywheel's axle 712. The magnetic unit 714 resists movement of the flywheel 706. Thus, the movement of the pull cable and the movement of the crank pedals and linkage pedals are resisted with 60 the same flywheel.

GENERAL DESCRIPTION

In general, the invention disclosed herein may provide users with an exercise machine that has several exercise modes. For example, the exercise machine may have a mode

that allows the user to perform a rowing exercise, a cycling exercise, an elliptical exercise, another type of exercise, or combinations thereof.

In some examples, the exercise machine includes a frame. The frame may include an upright portion and a base portion. The upright portion of the frame can be connected to a seat track that extends horizontally away from the upright portion. A leg may extend vertically from the base and support a distal end of the seat track. A seat may be movably attached to the seat track so that the seat can slide along a length of the seat track.

The upright portion may support a pull cable. A first end of the pull cable may be attached to a handle, and a second end of the pull cable may be attached to a resistance mechanism. In some examples, the resistance mechanism is contained within a housing that is connected to the upright portion of the frame. In those circumstances when the pull cable is pulled, the resistance mechanism resists the longitudinal movement of the pull cable. The housing, the upright portion, or another portion of the exercise machine may include a push pad. A user may sit on the seat and place his or her feet against the push pads. The user may slide along the length of the seat track by extending his or her legs and/or bending her or her knees. As the user's seat slides away from the upright portion of the frame, the user may lean back and pull the pull cable as part of a rowing exercise. As the user travels towards the upright portion of the frame, the pull cable may longitudinally move to return to its original position.

The base may include at least one structural member that is transverse the upright portion. In some examples, the base includes multiple structural members that are aligned with each other and also transverse the upright portion. The base may include a first linkage track and a second linkage track. In some cases, the first linkage track is formed on a first side of the base, and the second linkage track may be formed on a second side of the base. In other examples, the first and second linkage tracks are incorporated into the base on a top side. The first linkage track and the second linkage track can be aligned with the seat track.

A crank assembly may be included in the exercise machine. In some examples, the crank assembly is supported by a section of the base. In other examples, the crank assembly is supported by a section of the upright portion. The crank assembly may include a crank axle, a first crank arm connected to the crank axle, and a second crank arm connected to the crank axle. A first crank pedal may be attached to the first crank arm, and a second crank pedal may be attached to a second crank arm. When the crank axle is rotated, the first crank pedal and the second crank pedal may travel in a generally circular path.

A first swing arm may be pivotally attached to a first side of the upright portion, and a second swing arm may be pivotally attached to a second side of the upright portion. A first swing handle may be attached to an upper portion of the first swing arm, and a second swing handle may be attached to an upper portion of the second swing arm. A bottom portion of the first swing arm may be connected to a first movable linkage, and a bottom portion of the second swing arm may be connected to a second movable linkage. The first movable linkage may have an end that slides along the length of the first linkage track of the base, and the second movable linkage may have an end that slides along the length of the second linkage track of the base. The other end of the first movable linkage may be connected to the first crank arm, and the other end of the second movable linkage may be connected to the second crank arm. A first linkage

pedal may be incorporated into a first mid-region of the first movable linkage, and a second linkage pedal may be incorporated into a second mid-region of the second movable linkage. The first and second linkage pedals may travel in an oblong path when the crank axle rotates.

Thus, in one mode, the user may perform a rowing exercise by pulling on the pull cable while sliding his or her body along the length of the seat track in the seat. In a second mode, the user may perform an elliptical trainer exercise by standing on the linkage pedals and rotating the crank axle with the linkage pedals. In some examples, the user may hold onto the first and second swing handles during the performance of the elliptical trainer exercise. Also, the user may perform a cycling exercise by pushing the crank pedals with his or her feet. In some cases, the seat may be locked in place along the length of the seat track so that the seat cannot slide. When locked, the user may sit on the seat and move the crank pedals with his or her feet to perform the cycling exercise.

In some examples, the resistance mechanism includes a crank wheel concentrically connected to the crank axle. The crank axle may be supported by a beam that is attached to a frame member of the upright portion and a leg connected to a base member of the frame. While this example is described with the crank axle supported with a specific component of the exercise machine, the crank axle may be supported with any appropriate component of the exercise machine.

A first transmission medium, such as a drive belt, chain, loop, rope, cable, band, and so forth, may be secured around the circumference of the crank wheel. In other examples, the first transmission medium can be secured around a portion of the crank axle's circumference. The first transmission medium may connect the crank wheel/crank axle to a first axle of a first flywheel. A first magnetic unit may be positioned adjacent the first flywheel so that the first magnetic unit resists the flywheel's movement. This resistance may be transmitted back through the first transmission medium to the crank axle. Thus, the rotational movement of the crank axle is also resisted. As a result, the movement of the crank pedals and the linkage pedals is also resisted.

The pull cable may be routed by the frame member of the upright portion. A second end of the pull cable may be connected to a pull cable axle which is supported by the beam or another portion of the exercise machine in other examples. In some examples, a second transmission medium may connect the pull cable axle to a second axle of a second flywheel. In this example, a second magnetic unit may be positioned adjacent the second flywheel so that the second magnetic unit resists the flywheel's movement. This resistance may be transmitted back through the second transmission medium to the pull cable axle and thereby resist the longitudinal movement of the pull cable. In this example, the movement of the crank axle and the movement of the pull cable axle are independent, so that movement of one of the these axles does not cause the rotation of the other. Thus, when the pull cable is moved, the crank pedals and the linkage pedals do not move accordingly. Likewise, when the crank pedals and/or linkage pedals are moved, no additional resistance is placed on the pull cable.

The magnetic unit may resist the movement of its respective flywheel. In examples where the magnetic unit exhibits a consistent magnetic field, the amount of resistance applied to the flywheel may be changed by moving the magnetic unit towards or away from the flywheel. For example, the resistance applied to the flywheel may be increased by moving the magnetic unit closer to the flywheel. In other

11

examples, the resistance applied to the flywheel may be decreased by moving the magnetic unit closer to the flywheel. In some cases, the magnetic unit may emit a variable amount of magnetic resistance by applying a varying amount of electrical power to the magnetic unit.

In other examples, the crank axle and the pull cable axle are connected to the same flywheel. In these types of examples, the first transmission medium and the second transmission medium are connected to the flywheel's axle. The magnetic unit resists movement of the flywheel. Thus, the movement of the pull cable and the movement of the crank pedals and linkage pedals are resisted with the same flywheel.

In some of these examples, longitudinal movement of the pull cable may also cause the crank pedals and the linkage pedals to travel along their respective paths. However, in other examples, the movement of the pull cable is still decoupled from the movement of the crank and linkage pedals. For example, a transmission medium connecting the crank axle to the flywheel axle may be connected with a spool assembly. The spool assembly may be connected to the flywheel axle so that when the spool assembly rotates in a first direction, the spool assembly causes the flywheel axle to rotate in the first direction. When the spool assembly rotates in a second direction with respect to the flywheel axle, the spool assembly rotates independent of the flywheel axle. As a result, when the flywheel axle rotates by a force other than the rotational force of the spool assembly, the spool assembly does not rotate. In this example, when the flywheel axle is caused to rotate by the transmission medium connected to the pull cable assembly, the spool assembly does not rotate. Likewise, the transmission medium connecting the pull cable axle to the flywheel axle can also be connected with a spool assembly so that movement of the pull cable is also independent of the crank axle's movement. In this manner, the movement of the pull cable axle and the crank axle are independent. Thus, pulling on the pull cable may not cause the crank and linkage pedals to move. Similarly, moving the crank pedals and/or linkage pedals may not apply a longitudinal force on the pull cable.

In some examples, the crank assembly does not include a crank wheel. In some of these examples, a transmission medium may connect the crank axle directly to the flywheel axle or to the circumference of the flywheel. In another example, the pull cable may be wrapped around a circumference of the flywheel so that as the handle of the pull handle is pulled, the flywheel is caused to rotate in a first direction. In other examples, a spring mechanism, a counterweight mechanism, or another type of mechanism causes the flywheel to return to its original orientation in the absence of a force from the user. In these examples, as the user reduces the pull force on the handles, the flywheel may return to its original position, ready to be rotated again in response to a pull force on the handles.

In other examples, the cable may be wrapped in a spool that is connected to the flywheel. In these examples, the spool may share a common rotational axis with the flywheel. The flywheel may rotate with the spool in a first direction when the user is pulling on the pull handle. However, the spool may rotate independent of the flywheel back to its original position as the user returns the pull handle to take up the slack in the cable. The spool may return to its original position due to a counterweight, a spring mechanism, another type of mechanism or combinations thereof. In these examples, the flywheel may remain in the orientation left by the user at the end of the user's pull. In this manner, the flywheel may rotate in just a single direction.

12

In some examples, the first flywheel and the second flywheel are positioned on the same rotational axle. In this example, the first and second flywheels can be positioned adjacent to one another. The first and second flywheels may be rotationally independent of each other and/or rotationally independent of the common axle. In this manner, the flywheels can rotate without affecting the momentum of the other flywheel. For example, at least one of the flywheels may be connected to the common axle with a rotational bearing that allows the flywheel to rotate independent of the common axle. In examples with a common axle, the common axle may be rotationally fixed with respect to the frame of the exercise machine.

In some cases, the seat track may include a fold joint so that the seat track may be moved upright to save space in a storage mode. The fold joint may occur at an end of the seat track proximate the upright portion of the frame, or the fold joint may be positioned in a mid-region of the seat track.

With the flywheel rotating in just a single direction, a sensor may track the number of revolutions performed by the flywheel. In some embodiments, the sensor causes a counter to be incremented up one for each rotation of the flywheel. In other embodiments, the sensor can track partial revolutions of the flywheel. Other sensors can track the magnetic resistance applied to the flywheel's rotation.

The tracked level of resistance and the revolution count can be sent to a processor within the exercise machine or remote of the exercise machine. Based on these inputs, the processor can be caused to determine the amount of calories burned during each pull and/or collectively during the course of the entire workout. Further, the force generated by each pull can be calculated as well. In some examples, a transmitter incorporated into the exercise machine may send the calorie count, the revolution count, a calculated force, a speed, a duration of the exercise, another type of information or combinations thereof to a remote device. This remote device may be a mobile device, a cloud based device, a networked device, another type of device, or combinations thereof. This information may be stored in a database. This database may be accessible to the user through the internet, a profile, a network or combinations thereof.

In some examples, other types of information can be determined using the revolution count. For example, the processor may also determine the expected remaining life of the exercise machine based on use. This number may be based, at least in part, on the number of flywheel revolutions. Further, the processor may also use the revolution count to track when maintenance should occur on the exercise machine, and send a message to the user indicating that maintenance should be performed on the exercise machine based on usage.

In some examples, the sensor is accompanied with an accelerometer. The combination of the inputs from the accelerometer and the sensor can at least aid the processor in determining the force exerted by the user during each pull, crank pedal rotation, and/or linkage pedal rotation. The processor may also track the force per pull, the average force over the course of the workout, the trends of force over the course of the workout and so forth. For example, the processor may cause a graph of force per pull to be displayed to the user. In this type of graph, the amount of force exerted by the user at the beginning of the workout versus the end of the workout may be depicted. This information may be useful to the user and/or a trainer in customizing a workout for the user.

The number of calories burned by the user per pull and/or rotation may be presented to the user in a display incorpo-

rated into the exercise machine or the display of a remote device (e.g. mobile device, laptop, etc.). In some examples, the calories for an entire workout are tracked and presented to the user. In some examples, the calorie count is presented to the user through the display, through an audible mechanism, through a tactile mechanism, through another type of sensory mechanism or combinations thereof.

In some cases, a console is connected to the upright structure. The console may include a display, an input mechanism for controlling various features and/or operational controls of the exercise machine, an energy efficiency indicator, a speaker, a fan, another component of the exercise machine, or combinations thereof.

The console may locate the input mechanism within a convenient reach of the user to control the operating parameters of the exercise machine. For example, the control console may include controls to adjust the strength of the resistance mechanism, adjust a volume of a speaker integrated into the exercise machine, adjust an incline angle of the seat track, select an exercise setting, control a timer, change a view on a display of the control console, monitor the user's heart rate or other physiological parameters during the workout, perform other tasks, or combinations thereof. Buttons, levers, touch screens, voice commands, or other mechanisms may be incorporated into the console incorporated into the exercise machine and can be used to control the capabilities mentioned above. Information relating to these functions may be presented to the user through the display. For example, a calorie count, a timer, a distance, a selected program, an incline angle, a decline angle, a lateral tilt angle, another type of information, or combinations thereof may be presented to the user through the display.

The console assembly may further include a pair of handles that the user may grip during the performance of an exercise. For example, the user may grip the handles attached to the console assembly when the user is in the upright position. A pair of handles incorporated into the seat may be within a convenient arms reach for the user while performing an exercise in the cycling mode. While the examples above have described the handles/arm supports that the user can used during the performance of different exercises in the exercise machine's different exercise modes, the user may grip any of the handles/arm supports within a convenient reach of the user and/or desirable by the user.

In some cases, at least some of the information used to determine the calorie burn is based on a user profile that contains personal information about the user, such as height, weight, age, gender, health conditions, body composition, other types of personal information, or combinations thereof. The personal information may inputted into the console of the exercise machine. In other examples, the console may be in communication with a remote device that contains the user profile. For example, the console may be in wireless communication with a personal computer, a mobile device, a datacenter, a website, a network device, another type of device, or combinations thereof that contain at least one item of personal information about the user.

In some examples, the console may be in communication with a remote device that operates a fitness tracking program. In this example, some of the personal information may be received from the fitness tracking program. Also, in some cases, the console may send information about the user's workout to the fitness tracking program. This workout information may include the type and duration of the exercise, the resistance settings, the estimated number of calories burned, other types of information, or combinations thereof.

While the examples above have been described with reference to specific structures, the exercise machine may include any appropriate type of structure consistent with the principles described herein. For example, the specific linkage connection points and the swing arm arrangements may vary while still providing an exercise machine that includes modes for cycling, elliptical training, and/or rowing. Also, in some examples, the movable linkages are connected to the crank assembly at a different location than the crank arms. Additionally, the movable linkages may be connected to a rear crank mechanism rather than a linear track at the movable linkages' rear ends. Further, the linkage tracks may be located in a different location of the exercise machine than in the exercise machine's base. Further, the seat track may be positioned at any appropriate angle including a downward angle, an upward angle, a level angle, another type of angle, or combinations thereof.

What is claimed is:

1. An exercise machine, comprising:
a frame;

a seat track disposed on the frame;

a seat movably attached to the seat track;

a first flywheel connected to the frame at a front of the frame;

a second flywheel connected to the frame at the front of the frame;

a crank assembly in communication with the first flywheel;

a first crank pedal connected to the crank assembly;

a second crank pedal connected to the crank assembly;

a pull cable in communication with the second flywheel;

a handle attached to a first cable end of the pull cable;

a cable axle in communication with a second cable end of the pull cable;

a first linkage pedal;

a second linkage pedal;

a first swing arm connected to the frame and the first linkage pedal; and

a second swing arm connected to the frame and the second linkage pedal.

2. The exercise machine of claim 1, further comprising a first magnetic resistance mechanism associated with the first flywheel, wherein the first magnetic resistance mechanism is configured to resist movement of the first flywheel.

3. The exercise machine of claim 2, further comprising a second magnetic resistance mechanism associated with the second flywheel, wherein the second magnetic resistance mechanism is configured to resist movement of the second flywheel.

4. The exercise machine of claim 1, wherein the crank assembly comprises:

a crank axle;

a first crank arm connected to a first side of the crank axle; and a second crank arm connected to a second side of the crank axle;

the first crank pedal connected to the first crank arm; and the second crank pedal connected to the second crank arm.

5. The exercise machine of claim 4, wherein the crank assembly further comprises a crank wheel connected to the crank axle.

6. The exercise machine of claim 5, further comprising a transmission medium configured to transmit torque from the crank wheel to the first flywheel when the crank axle rotates.

7. The exercise machine of claim 4, wherein the first crank pedal and the second crank pedal travel in a generally circular path when the crank axle rotates.

15

8. The exercise machine of claim 4, further comprising:
a base connected to the frame;
a first movable linkage pivotally connected to the first side
of the crank axle and slidably connected to the base;
and
a second movable linkage pivotally connected to the
second side of the crank axle and slidably connected to
the base.

9. The exercise machine of claim 8, wherein the base
comprises:
a first linkage track; and
a second linkage track aligned with the first linkage track;
wherein the first movable linkage connects in the first
linkage track, and the second movable linkage connects
in the second linkage track.

10. The exercise machine of claim 9, wherein the first
swing arm is pivotally connected to the first movable
linkage, and the second swing arm is pivotally connected to
the second movable linkage.

11. The exercise machine of claim 9, wherein the first
linkage track and the second linkage track are aligned with
the seat track.

12. The exercise machine of claim 8, further comprising:
the first linkage pedal connected to a mid-region of the
first movable linkage; and
the second linkage pedal connected to a mid-region of the
second movable linkage.

13. The exercise machine of claim 12, wherein the first
linkage pedal and the second linkage pedal travel in a
generally oblong path when the crank axle rotates.

14. The exercise machine of claim 1, further comprising
a transmission medium connecting the cable axle to the
second flywheel.

15. An exercise machine, comprising:
a frame including a housing at one side of the frame;
a seat track disposed on the frame;
a seat movably attached to the seat track of the frame;
a first flywheel connected to the frame and contained
within the housing;
a second flywheel connected to the frame and contained
within the housing;
a crank assembly in communication with the first fly-
wheel, the crank assembly including:
a crank axle;
a first crank arm connected to a first side of the crank
axle;
a second crank arm connected to a second side of the
crank axle;
a first crank pedal connected to the first crank arm; and
a second crank pedal connected to the second crank
arm;
a pull cable in communication with the second flywheel;
a first swing arm connected to the frame;
a second swing arm connected to the frame;
a base connected to the frame;
a first movable linkage pivotally connected to the first side
of the crank axle and slidably connected to the base;
a second movable linkage pivotally connected to the
second side of the crank axle and slidably connected to
the base;
a first linkage track;
a second linkage track aligned with the first linkage track;
a handle attached to a first cable end of the pull cable;
a cable axle in communication with a second cable end of
the pull cable;
a first linkage pedal connected to a mid-region of the first
movable linkage; and

16

a second linkage pedal connected to a mid-region of the
second movable linkage;
wherein the first movable linkage connects in the first
linkage track, and the second movable linkage connects
in the second linkage track;
wherein the first swing arm is pivotally connected to the
first movable linkage, and the second swing arm is
pivotally connected to the second movable linkage; and
wherein the first linkage track and the second linkage
track are aligned with the seat track.

16. The exercise machine of claim 15, wherein the first
linkage pedal and the second linkage pedal travel in a
generally oblong path when the crank axle rotates.

17. The exercise machine of claim 15, further comprising
a transmission medium connecting the cable axle to the
second flywheel.

18. An exercise machine, comprising:
a frame including an upright portion at a front of the frame
and a base;
a seat track disposed on the frame and extending hori-
zontally away from the upright portion, wherein a distal
end of the seat track is supported by a leg;
a seat movably attached to the seat track of the frame;
a first flywheel connected to the frame and connected to
the upright portion;
a second flywheel connected to the frame and connected
to the upright portion;
a crank assembly in communication with the first fly-
wheel, wherein the crank assembly includes:
a crank axle;
a first crank arm connected to a first side of the crank
axle;
a second crank arm connected to a second side of the
crank axle;
a first crank pedal connected to the first crank arm;
a second crank pedal connected to the second crank
arm; and
a crank transmission medium that transmits torque
from the crank assembly to the first flywheel when
the crank axle rotates;
a pull cable in communication with the second flywheel
and supported by the upright portion;
a first swing arm connected to the frame;
a second swing arm connected to the frame;
the base connected to the frame;
a first movable linkage pivotally connected to the first side
of the crank axle and slidably connected to the base;
a second movable linkage pivotally connected to the
second side of the crank axle and slidably connected to
the base;
a first linkage track;
a second linkage track aligned with the first linkage track;
a first linkage pedal connected to a mid-region of the first
movable linkage; and
a second linkage pedal connected to a mid-region of the
second movable linkage;
a handle attached to a first cable end of the pull cable;
a cable axle in communication with a second cable end of
the pull cable;
a pull transmission medium connecting the cable axle to
the second flywheel;
wherein the first movable linkage connects in the first
linkage track, and the second movable linkage connects
in the second linkage track;
wherein the first swing arm is pivotally connected to the
first movable linkage, and the second swing arm is
pivotally connected to the second movable linkage; and

wherein the first linkage track and the second linkage track are aligned with the seat track; and wherein the first linkage pedal and the second linkage pedal travel in a generally oblong path when the crank axle rotates and the first crank pedal and the second 5 crank pedal travel in a generally circular path when the crank axle rotates.
